(57) **CLAIM**

The ornamental design for a robotic ultra high pressure surface coating removal device, as shown and described.

DESCRIPTION

FIG. 1 is a perspective view of the robotic ultra high pressure surface coating removal device of the instant invention;

FIG. 2 is a top view thereof;

FIG. 3 is a right side view thereof;

FIG. 4 is a left side view thereof;

FIG. 5 is a front view thereof;

FIG. 6 is a rear view thereof; and,

FIG. 7 is a bottom view thereof.

The broken lines in the drawings depict portions of the robotic ultra high pressure surface coating removal device which form no part of the claimed design.
